UNITED STATES PATENT OFFICE.

ALBIN H. WARTH, OF BALTIMORE, MARYLAND, ASSIGNOR TO THE CROWN CORK & SEAL COMPANY OF BALTIMORE CITY, OF BALTIMORE, MARYLAND, A CORPORATION OF MARYLAND.

APPARATUS FOR GAS-TREATING ARTICLES.

Application filed February 5, 1926. Serial No. 86,199.

This invention relates to apparatus for gas treating articles, such, for example, as cork disks and plugs.

In a Patent Number 1,524,494, dated Jan. 27, 1925, I have disclosed a novel process for treating composition cork disks and plugs with a toxic gas which will not injure the cork, for the purpose of destroying or preventing the development of mold 10 spores, bacteria, fungous growths, yeasts, insect larvae, etc.

It is an object of the present invention to produce an improved apparatus for commercially and effectively treating composition articles according to the process referred to.

With this general object in view, the invention consists in the features, combinations, details of construction, and arrangements of parts which will first be described in connection with the accompanying drawings and then more particularly pointed out.

In the drawings—

Figure 1 is a view partly in vertical section and partly in side elevation of an apparatus constructed in accordance with the invention;

Figure 2 is a top plan view of the same, and,

Figure 3 is a detail view showing enlarged and partly in section and partly in elevation, a portion of the apparatus.

Referring to the drawings, there is provided a container for a mass of articles to be treated, and in structures embodying the invention to the best advantage, the container will enclose a substantially unobstructed chamber for the articles and will have relatively large top and bottom openings to permit an unobstructed gravity flow of the articles. In the embodiment here shown as an example a cylindrical container 11 encloses a substantially unobstructed treatment chamber 12. In the top of this container is a relatively large feed opening 13 for the reception of the articles. Above the opening is a feeding funnel 14. The feed opening 13 is closed, during treatment, by a closure or lid 15 clamped in place by a screw 16 working in a cross arm 17 which takes under lugs 18 in the funnel. The lid has a sealing gasket 19 for effecting a substantially gas-tight seal.

The container 11 is slightly tapered at the bottom and has a relatively large discharge

opening normally closed by a sliding shutter 21. A receiving bag 22 is supported under the bottom opening by hooks 23.

There is provided means for conducting a toxic gas to each end of the container and in structures embodying the invention to the best advantage there will be a main supply and a supplemental supply. The main gas supply may be conveniently accomplished by a gas distributor having distributing portions located both crosswise and lengthwise of the chamber. Although capable of various constructions, in that here shown as an example, located centrally of the treatment chamber 12, is a main gas distributor in the form of a T-shaped pipe 25, the cross piece of which is near the top of the chamber and the leg of which extends nearly to the bottom of the chamber. In both the cross piece and the leg of this distributor are a number of spaced gas outlet ports 26. The T-shaped distributor 25 is connected by a branch pipe 27 with a common delivery pipe 28.

While the supplemental gas supplying means may vary, as here shown as an example, at the lower end of the container is a pipe 29 set into the container wall with its end opening into the treatment chamber. This pipe is connected by a branch pipe 30 with the common delivery pipe 28.

Means is provided for so determining and controlling the gas flow that the gas is admitted to the container at a predetermined rate. This may be accomplished by a gas pressure chamber between the source and the container, a device for indicating the pressure, and a regulating or controlling valve for the supply. In the embodiment here shown as an example, mounted in a housing 41, above the container 11, is a cylindrical tank 42 having end caps 43, 44 and enclosing a pressure chamber 45. In the bottom cap 44 is a gas supply pipe 46 coupled to a main 47 which is connected with a source of gas under pressure, such as the ordinary gas cylinder, not shown. In the supply pipe 46 is a needle valve 48 for regulating the flow to the pressure chamber.

In the top cap 43 of the casing is a gas exit pipe 49 coupled to the common delivery pipe 28, which, as above described, delivers gas to the container. Pipe 49 extends into the tank (Fig. 3) a short distance and has an end cap 50 in which is a restricted gas

port 51. While the size of this opening may vary, for a $\frac{1}{8}$ " supply pipe and a $\frac{1}{4}$ " exit pipe, a $\frac{3}{16}$ " port has been found suitable.

Adjacent the pressure chamber is a U-shaped tube 55 containing a column of mercury 56. Connected with one leg of the mercury tube is a pipe 56^A leading from a nipple 57 in the top cap 43 of the pressure chamber. On the other leg of the mercury tube is a glass bulb 58 into which extends a glass tube 59 terminating in a curved portion at the end of which is a restricted opening. The glass tube 59 is connected with a pipe 60 leading from exit pipe 49 at a point outside the pressure chamber, i. e. beyond the opening 51. Thus, the respective ends of the mercury column are in communication with the gas supply at opposite sides of opening 51.

20 Associated with the mercury column is a scale 61 which may conveniently be calibrated to show the volume of gas per hour.

There is provided valve means for regulating the relative amounts of gas admitted to the respective ends of the container. As here shown as an example, in the branch pipe 30, near its junction with the common delivery pipe 28, is a control valve 31. In branch pipe 27 is a similar control valve 32. The rate of total flow is determined and controlled by the means previously described but the relative amounts for the main and supplemental deliveries may be regulated by proper manipulation of the valves 31, 32. This makes possible an even distribution of gas throughout the mass of articles.

40 A needle valve 71 in the end of branch pipe 30 permits inspection of the supplemental flow, as by opening the valve and allowing the gas to bubble out through water.

There is provided means for exhausting any residual gas after treatment. As here shown as an example, near the lower end of tank 11 is an exhaust pipe 33 having a sliding door 34 and leading to a fan blower, indicated conventionally at 35, of any suitable construction.

50 In operation, lid 15 being removed and slide 21 closed, a mass of articles to be treated is dumped into the tank 11. While various articles may be treated the apparatus is particularly adapted to the treatment of composition cork disks for use as sealing disks in closures of the well-known crown cork type. Such disks are shown in Fig. 1. When the tank is filled with disks the lid 15 is replaced and the gas turned on by means of valve 48. The gas from main 47 enters chamber 45 and passes out through opening 51 in exit pipe 50 to delivery pipe 28 which conducts it to the gas distributor 25. Here it flows out of the gas outlet ports 26 in the cross piece and leg of the distributor and gradually diffuses through the mass of corks, partly or entirely displacing the air in the

5 pores of the cork. As a result any mold spores, bacteria, fungous growth, yeasts, insect larvae, etc. which may be in the cork or in the binder by which the cork granules are held together, either will be destroyed by the gas or their development will be inhibited because of the absence of air necessary to such development. Meanwhile some gas from common delivery pipe 28 is delivered to the container by way of the branch pipe 30 and pipe 29. The main supply enters by the distributor 25 but pipe 29 provides small auxiliary supply to equalize the time of treatment for the disks at the bottom of the container.

80 After the gas is turned on, due to the restricted exit opening 51, gas pressure builds up in tank 42 and this pressure is indicated by the mercury column, showing by means of scale 61, the volume of gas per hour. As pointed out in the patent referred to, the gas treatment should be so conducted that the cork will not be over-saturated with the gas for a given product. By observing the relation of the mercury column to the scale, 85 and by manipulation of needle valve 48, the desired rate of flow is obtained. At the end of the saturation period, which may be from four to eight hours, according to the amount of gas admitted, the size of the container, 90 etc., the gas is shut off by valve 48. Sliding door 34 is opened and the fan 35 started to exhaust any residual gas. The bottom door or shutter 21 is then opened and the cork disks flow out by gravity into the bag. 100

As pointed out in the patent referred to, sulphur dioxide has been found to give satisfactory results. Other gases may, however, be used.

With the construction described, the toxic 105 gas may be evenly distributed to the mass of articles while quiescent in the container; the gas-distributing means presents a minimum obstruction to the gravity flow of the disks into and out of the container; and the rate 110 of flow is effectively determined and controlled.

Certain features of the above described apparatus are claimed in a co-pending application, Serial No. 453,530, filed March 18, 115 1921, Patent No. 1,610,339.

What is claimed is:

1. In an apparatus of the class described, and in combination, a container for articles to be treated, a gas delivery pipe adapted for connection with a source of gas supply, a branch pipe leading from the delivery pipe to one end of the container, a second branch pipe leading from the delivery pipe to the other end of the container, means for so determining and controlling the gas flow that the gas is admitted to the container at a given rate, and valve means for regulating the relative amounts of gas admitted to the respective ends of the container. 130

2. In an apparatus of the class described, and in combination, a container for articles to be treated, a T-shaped gas distributing pipe in said container having a plurality of gas outlet ports in both the leg and cross piece of the T, a gas delivery pipe adapted for connection with a source of gas supply, a connection between the distributing pipe and the delivery pipe, a branch pipe connected with the delivery pipe and having communication with the interior of the container at the end thereof opposite the cross piece of the T, and a control valve in said branch pipe.
- 10 3. In an apparatus of the class described, and in combination, an upright container for articles to be treated, a relatively large top opening for feeding the articles into the container, a relatively large bottom opening for the discharge of the articles, closures for said openings, a T-shaped gas dis-
- tributing pipe in the container, said pipe having a plurality of spaced outlet ports in both the leg and cross piece of the T, a gas delivery pipe for connecting said distributing pipe with a source of gas supply, and a supplemental gas delivery pipe having its end set in the wall of the container at the end of the container opposite the cross piece of the T.
- 25 4. In an apparatus of the class described, and in combination, a container for articles to be treated, means for conducting gas to opposite ends of the container, means for so determining and controlling the gas flow that the gas is admitted to the container at a given rate, and means for regulating the relative amounts of gas admitted to the respective ends of the container.
- 30 In testimony whereof, I have hereunto set my hand.
- 35 ALBIN H. WARTH.
